TOY SLIPPER

Filed Nov. 14, 1930

INVENTOR
Rose Wiesner
BY *Solman H. Olachuk*
ATTORNEY

UNITED STATES PATENT OFFICE

ROSE WIESNER, OF JAMAICA, NEW YORK

TOY SLIPPER

Application filed November 14, 1930. Serial No. 495,548.

This invention relates to new and useful improvements in a moving eye for a slipper.

The invention has for an object the provision of a moving eye for a slipper formed mainly from material in the form of a slipper with a downturned collar at its top edge which is opened at the front, a figure on the vamp of the slipper and the front of the collar, and eyes upon the figure arranged

10 to move.

It is a still further object of this invention to form the figure of two sheets secured together along a portion of their edges and arranged to have free portions for extending beneath the collar and bottom portions for resting upon the vamp of the shoe so that during walking vibrations occur which are transmitted to move the eyes of the figure.

20 As a still further object of this invention it is proposed to provide a casing with an opened side simulating an eye, a transparent cover on said casing, and a small colored disc within the casing simulating an eyeball which is arranged to move during walking.

As a further object of this invention it is proposed to provide upon the transparent cover a rim which may engage upon the 30 corresponding rim on the casing to connect the parts together.

As a still further object of this invention it is proposed to provide a casing simulating the eye of the figure, arranged with a rear vertical slot through which a rod extends, connected with the eyeball of the eye, and a means for moving the rod to move the eyeball during walking.

40 A still further object of this invention is to provide a stem attached upon the rod mentioned in the previous paragraph and arranged to abut the vamp of the shoe so as to be urged upwards during walking, and 45 to provide a means for urging the stem downwards against the vamp.

As a still further object of this invention it is proposed to provide a device of the class mentioned which is of simple durable 50 construction, dependable in use and efficient

in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

55 In the accompanying drawings forming a material part of this disclosure:—

Fig. 1 is a side elevational view of a slipper constructed according to this invention.

Fig. 2 is a plan view of Fig. 1.

Fig. 3 is a fragmentary sectional view 65 taken on the line 3—3 of Fig. 1, and showing the figure.

Fig. 4 is a fragmentary enlarged sectional view taken on the line 4—4 of Fig. 1.

Fig. 5 is an enlarged sectional view of one 70 of the eyes of the figure.

Fig. 6 is a similar view to Fig. 1, but showing a modified form of the invention.

Fig. 7 is a fragmentary sectional view 75 similar to Fig. 3 but taken on the line 7—7 of Fig. 6.

Fig. 8 is a similar view to Fig. 5, but showing the modified form of the invention.

The movable eyed slipper comprises material in the form of a slipper 10 having 80 a downturned collar 11 on its top edge 12, a figure 13 on the vamp 14 of the slipper associated with said collar as a tie and comprising a pair of silhouette congruent sheets 15 and 16 secured together along a portion 85 17 of their edges so that other portions 18 extend beneath said collar 11 and other portions 19 rest upon the vamp of said slipper, and eyes 20 with movable eyeballs 21 attached on the sides of the figure 13. 90

The slipper 10 may be of any design and construction, but preferably it should be formed with an upper of felt and with a sole and heel of soft leather. The figure 13 is in the form of a rabbit's head. The secured portion 17 extends from the neck of the rabbit along over the face around the ears and a portion of the back of the head. The securing means are in the form of stitches. 95

The portions 18 project from the back of the head of the rabbit, and are pointed and extend through the opened portion of the collar thereunder just as a conventional bow tie. Staples 22 engage through the portions 18 and through the top portions of the slipper 10 to hold the animated figure in place. It should be noticed that these staples have an outer portion flush on the outer face of the portions 18 and transverse portions 22^a extending through both materials and then have their inner ends turned towards each other. The transverse portions 22^a constitute two points of support for each of the portions 18, to prohibit pivoting of the figure.

The portions 19 are spread away from each other, as clearly illustrated in Figs. 3, and 7, and having their edges curved, shown in Fig. 1. These curved edges rest upon the vamp of the shoe and as walking occurs spread so that the head of the figure is not materially raised.

The eyes 20 are in the form of casings 23 glued or otherwise attached upon the outer sides of the sheets 15 and 16, at the points where the eyes naturally appear. Transparent covers 24 of glass, celluloid or other similar material are engaged upon the casings 23. The covers and the casings have flanges directed towards each other which may overlap to accomplish the engagement. A colored disc 21 is arranged within each of the casings and constitutes the eyeball of the eye.

In the illustrations shown in Figs. 6 and 7, a pin 26 rigidly connects the disc 21 and in so doing extends through slots formed in the casing 23 in the sheets 15 and 16. The eyes 20 necessarily must be directly in line with each other. A stem 28 is rigidly attached upon the pin 26 and extends downwards through a channel 29 formed between the sheets 15 and 16. This channel is formed by stitches 30 on opposite sides of the stem, as clearly shown in Fig. 6. A spring seat 31 is positioned at the bottom of the passage 29, as clearly shown in Fig. 7, and holds one end of an expansion spring 32 having its other end resting against a collar 33 rigidly attached upon the stem 28. The stem 28 slidably engages through the spring seat 31 so that the spring acts to urge the stem down upon the vamp of the shoe. In Fig. 7 the vamp is indicated by dot and dash lines 34, and it should be noticed that the stem is resting on it.

During walking, the foot is bent at the toes and causes the figure 13 to move downwards relative to the vamp since it is supported at the points 22. The portions 19 spread to allow this downward motion. Since the stem 28 rests on the vamp of the shoe, it cannot move downwards, and the 55 downward motion causes a relative upward

motion of the eyeballs 21 which constitute the moving eyes. As soon as the foot is straightened out, the spring 32 will return the parts to normal positions into the eyeballs 21 which are disposed at the bottom of the casing as shown on the drawings. Dot and dash lines 35 in Fig. 8 indicate the raised position of the eyeball.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. An article of footwear, comprising material in the form of a slipper having a top edge, a figure above the vamp of said slipper comprising a pair of silhouette congruent sheets secured together along portions of their edges so that other free portions extend beneath said top edge and on the vamp of said slipper, eyes with movable eyeballs attached on the sides of said figure, and staples engaging through the portions of the figure disposed beneath said top edge for holding the figure against pivoting.

2. An article of footwear, comprising material in the form of a slipper having a downturned collar on its top edge, a figure above the vamp of said slipper associated with said collar as a tie and comprising a pair of silhouette congruent sheets secured together along portions of their edges so that other free portions extend beneath said collar and on the vamp of said slipper, eyes with movable eyeballs attached on the sides of said figure, and staples engaged through the portions of the figure disposed beneath said collar for holding the figure against pivoting, said staples being arranged with a pair of transverse portions engaged through the materials to prohibit the pivoting and to hold the bottom portions of said congruent sheets in contact with said vamp.

3. An article of footwear, comprising material in the form of a slipper having a downturned collar on its top edge, a figure above the vamp of said slipper associated with said collar as a tie and comprising a pair of silhouette congruent sheets secured together along portions of their edges so that other free portions extend beneath said collar and on the vamp of said slipper, and eyes with movable eyeballs attached on the sides of said figure, the portions of the figure which rest upon the vamp are separated from each other and have curved bottoms so as to raise during walking for vibrating said eyeballs.

4. An article of footwear, comprising

material in the form of a slipper having a top edge, a figure above the vamp of said slipper comprising a pair of silhouette congruent sheets secured together along portions of their edges so that other free portions extend beneath said collar and on the vamp of said slipper, eyes with movable eyeballs attached on the sides of said figure, and means for moving said eyeballs during walking.

5. An article of footwear, comprising material in the form of a slipper having a downturned collar on its top edge, a figure above the vamp of said slipper associated with said collar as a tie and comprising a pair of silhouette congruent sheets secured together along portions of their edges so that other free portions extend beneath said collar and on the vamp of said slipper, eyes 15 with movable eyeballs attached on the sides of said figure, and means for moving said eyeballs during walking, comprising a transverse pin connected between the eyeballs and extending through slots formed in the eyes 20 and the material of the figure, a stem connected with said transverse pin and extending through a channel between the sheets constituting the figure, and means for normally urging said stem downwards 25 against the vamp of the slipper.

In testimony whereof I have affixed my signature.

ROSE WIESNER.
